CLAIM

The ornamental design for an electronic capsule, as shown and described.

DESCRIPTION

FIG. 1 is a rear view of a first embodiment of an electronic capsule;

FIG. 2 is a front view of a first embodiment of an electronic capsule;

FIG. 3 is a top view of a first embodiment of an electronic capsule;

FIG. 4 is a bottom view of a first embodiment of an electronic capsule;

FIG. 5 is a left-side view of a first embodiment of an electronic capsule;

FIG. 6 is a right-side view of a first embodiment of an electronic capsule;

FIG. 7 is a perspective view of a first embodiment of an electronic capsule;

FIG. 8 is a rear view of a second embodiment of an electronic capsule;

FIG. 9 is a front view of a second embodiment of an electronic capsule;

FIG. 10 is a top view of a second embodiment of an electronic capsule;

FIG. 11 is a bottom view of a second embodiment of an electronic capsule;

FIG. 12 is a left-side view of a second embodiment of an electronic capsule;

FIG. 13 is a right-side view of a second embodiment of an electronic capsule; and,

FIG. 14 is a perspective view of a second embodiment of an electronic capsule.
